UNITED STATES PATENT OFFICE.

GEORGE B. MATTHEWS, OF WASHINGTON, DISTRICT OF COLUMBIA.

ELECTRICAL INSULATOR.

Application filed March 31, 1923. Serial No. 629,079.

To whom it may concern:

Be it known that I, GEORGE B. MATTHEWS, citizen of United States, residing at 1109 17th Street NW., in the city of Washington, 5 District of Columbia, have invented certain new and useful Improvements in Electrical Insulators, of which the following is a specification.

This invention relates to electrical insulators, and has special reference to the type of insulator used in insulating one length of wire from another, the invention being peculiarly adapted for utilization in connection with wireless telegraphy and telephony 10 for the purpose of supporting the aerials in such system.

One important object of the invention is to improve the general construction of devices of this character.

20 A second important object of the invention is to provide an improved form of insulator of this character wherein the insulator is so constructed and arranged that the wiring connections are protected from the action of rain, snow and sleet, so that at no 25 time can the two wires connected to the insulator be connected by a film of water from rain, an accumulation of snow, or a coating of ice resulting from sleet.

30 With the above and other objects in view as will be hereinafter apparent, the invention consists in general of certain novel details of construction and combinations of parts hereinafter fully described, illustrated 35 in the accompanying drawings and specifically claimed.

In the accompanying drawings like characters of reference indicate like parts in the several views, and:

40 Fig. 1 is a plan view of a preferred form of the improved insulator.

Fig. 2 is a side elevation thereof.

Fig. 3 is a vertical longitudinal section therethrough.

45 Fig. 4 is a side elevation of a second form of insulator.

Fig. 5 is a vertical longitudinal section through the second form.

50 Fig. 6 is a plan view of the second form.

In the embodiment of the invention, as 55 illustrated in Figures 1, 2 and 3, it will be seen that there is provided the usual short spindle-shaped body 10 having at each end a peripheral flange or skirt 11, and projecting at or slightly above the center of this body, from each end thereof, is a con-

necting eye 12 for the purpose of joining the wires to the insulator. From the upper and side portions of this insulator projects a hood or housing, which in this form is made integral with the insulator, and consists at each end of an upper housing portion 13 tapered to a point and provided along its tapering edges with concave portions 14 forming a species of trough.

In like manner, the hood or housing extends downward over the hood or sides of the insulator, as at 15, and terminates at each end in a pointed portion 16 curved to provide troughs 17 adjacent its end edges.

It will be noted that these portions project sufficiently far from the body of the insulator to cover the connecting eyes 12, and protect them against rain beating either downward or at a slant, and that by reason of the trough-shape arrangements at the end edges of the hood rain falling on top of the hood is carried off sideways, and thus is prevented from running back on the underside of the hood and down the end of the insulator.

It will also be noted that in order to assist in thus preventing the moisture from creeping back toward the insulator, the parts of the hood are inclined downward, as can be clearly seen by reference to Figure 3.

In the form shown in Figure 5, an ordinary stock insulator is used, which is provided as usual with the end skirt or flanges 19 and eyes 20. In this form the insulator 18 is soldered or leaded, as at 21 into a hood or housing which consists of an inverted trough-shape plate 22 having outwardly flaring sides, and having its ends closed by downwardly and outwardly inclined end plates 23 notched centrally at their bottom edge, as at 24, and having the diagonal portions at each side of the notches curved to provide directing troughs 25. Also each 100 of these end plates carries an upper centrally disposed guard member 26 protecting the upper part of the notch 24.

In certain instances, it is desirable to supply these insulators with means to prevent rotation thereof at their longitudinal axis. This is peculiarly necessary where twisted wires or cables are connected, because in such instances, the strain on these cables exerts a very considerable tortional effect on the insulator. In such instances I provide an arm 27 which is screwed into

the bottom of the insulator, and carries on its lower end a weight 28, which thus acts to hold the insulator against rotation through the force of gravity.

5. There has thus been provided a simple and efficient device of the kind described, and for the purpose specified.

It is obvious that minor changes may be made in the form and construction of the 10 invention without departing from the material spirit thereof. It is not, therefore, desired to confine the invention to the exact form herein shown and described, but it is desired to include all such as properly 15 come within the scope claimed.

Having thus described the invention, what is claimed as new, is:

1. An insulating device for connecting two wires in alinement which consists of an 20 insulating body provided with a hood projecting longitudinally from the peripheral portion of the body at the ends and extending downward over the sides of the body, said hood having moisture directing trough 25 portions at its end edges, the upper portions of the projecting ends of the hoods being inclined downward to prevent moisture from creeping back beneath the hood toward the insulator.

30 2. An insulating device comprising a substantially spindle-shaped body of insulating material having peripheral skirts at its ends and provided with a substantially spindle-shaped hood extending from the ends 35 of the body and downwardly over its sides, the ends of said hood being provided with

concave portions adjacent their edges constituting moisture directing troughs.

3. An insulating device comprising a substantially spindle-shaped body of insulating material having peripheral skirts at its ends and provided with a substantially spindle-shaped hood extending from the ends of the body and downwardly over its sides, the sides of said hood extending below the skirts of said body, the ends of said hood being provided with concave portions adjacent their edges constituting moisture 45 directing troughs.

4. An insulating device comprising a substantially spindle-shaped body of insulating material having peripheral skirts at its ends and provided with a substantially spindle-shaped hood extending from the ends of the body and downwardly over its 55 sides, the sides of said hood extending below the skirts of said body, the ends of said hood being provided with concave portions adjacent their edges constituting moisture 60 directing troughs, the projecting ends of said hood being notched at the sides whereby to form an upper tapered projection and lateral side projections.

5. An insulating device of the kind described comprising an insulating body, a 65 hood projecting over the ends of said body and downwardly over the sides of the body, said hood being permanently attached to said body, and a counterweight depending from the underside of the body.

In testimony whereof I affix my signature.

GEORGE B. MATTHEWS.
